UNITED STATES PATENT OFFICE.

HENRY B. SLATER, OF RIVERSIDE, CALIFORNIA.

ELECTROLYTIC CELL STRUCTURE.

1,231,955

Specification of Letters Patent.

Patented July 3, 1917.

Application filed March 21, 1914. Serial No. 826,210.

To all whom it may concern:

Be it known that I, HENRY B. SLATER, a citizen of the United States, residing at Riverside, in the county of Riverside and 5 State of California, have invented certain new and useful Improvements in Electrolytic Cell Structures, of which the following is a specification.

This invention relates to improvements in 10 electrolytic cell structures and particularly to the arrangement and construction of the anodes and diaphragms employed therein.

It is an object of the invention to provide a cell adapted for treating value carrying 15 solutions and particularly solutions containing metal values extracted from ores, for the removal of a part of the metallic constituents, being at the same time so acted upon as to convert them into a state of higher 20 valency and more active condition, so as to be valuable for further treating the same ore, in the extraction of any remaining metallic values thereof, or for treating other ore of the same kind as that originally 25 treated.

It is also an object of the invention to construct a vat or cell in which one or more sectional anodes may be employed, for obtaining any desired area of anode surface, 30 the structure being such that sections of the anode may be added or removed to secure such desired area.

It is a further object of the invention to provide a combined anode and diaphragm 35 for an electrolytic cell, the diaphragm being readily removable for cleansing and replacement.

It is a still further object of the invention to provide a hollow anode for an electrolytic 40 cell and a removable casing or sleeve forming a diaphragm for preventing the commingling of certain constituents of the materials treated in the cell.

It is a further object of the invention to 45 provide an electrolytic cell with an anode constructed so that fluids from the cell may flow out through the said anodes, a dia- 50 phragm of porous material being arranged to surround the anode whereby it will be supported thereon without other fastenings.

With these and other objects in view, the invention comprises certain novel constructions, combinations and arrangements of

parts as will be hereinafter fully described and claimed.

In the accompanying drawing forming a part of this specification:

Figure 1 is a top plan view of an electrolytic cell structure constructed in accordance with the present invention.

Fig. 2 is a side elevation of the said cell, a part of its walls being broken away and shown in section to better reveal the interior structure.

Fig. 3 is a transverse vertical sectional view through the said cell taken upon line 65 3-3 of Fig. 1.

Fig. 4 is a detail fragmentary sectional view showing a portion of the cell upon an enlarged scale and some of the sections of 70 one of the anodes.

Fig. 5 is an enlarged detail view, partially in side elevation and partially in section of one of the members of the anode, the diaphragm inclosing the same being also partially shown.

Fig. 6 is a detail fragmentary view of a portion of the cell showing a different form of outlet connections from the anode branches of the cell, from that shown in 80 Fig. 1.

While the cell structure forming the subject matter of the present invention is adapted for the treatment and electrolysis of various substances and solutions, it is 85 particularly well adapted for the treatment of solutions which have been employed for extracting copper and other metallic values from ores, such for instance as that described in my previous Patent No. 1,066,855 90 granted July 8, 1913. The cell of the present invention is especially useful in precipitating copper from the mixed solution of sodium chlorid, ferrous chlorid and cuprous chlorid mentioned in said patent.

The direct electrolysis of such a solution for the extraction of copper, without the intervention of a baffle or diaphragm, is economically impractical because of the formation and diffusion of cupric and ferric compounds throughout the solution, these compounds being active solvents of copper, dissolving the copper deposited at the cathode of an ordinary cell, about as fast as it is formed, and eventually eating off the 105 cathode at the surface of the solution so as

to allow the lower part of the cathode to drop to the bottom of the vat or cell. If however these cupric and ferric compounds are removed as fast as formed, being replaced by a continuous supply of cuprous and ferrous solution, the cathode will continue to build up with an even reguline deposit of copper of great purity. The structure of the cell forming the subject matter of the present invention is well adapted for facilitating the treatment of these substances and the details and features of the said structure will now be more specifically described and claimed.

15 In the accompanying drawing, a preferred form of the cell structure and of the anodes and diaphragms employed therein have been illustrated.

16 In said structure 5 indicates a vat, receptacle or cell within which the materials to be treated by electrolysis are placed. The said cell may be of concrete, wood, iron or any suitable material which should be lined with an insulating and acid-proof paint or 20 varnish. Extending across the cell at suitable intervals are cathodes 6, usually of copper and having projecting end portions 7 and 8 at their upper corners for supporting them upon the walls of cell 5. The projections 8 extend sufficiently far beyond the walls of the cell to facilitate their connection with a bus-bar 9 by which they may all be connected with an electric conductor and a source of electric energy.

30 25 35 The anodes and their structures form important features of the present invention and the said anodes are so made that the solutions introduced into the cell for treatment may flow out therefrom through the said anodes. The anodes are preferably connected with an outflow pipe 10 which is provided with T-connections 11 at the intervals where the anodes are to branch therefrom. Other T-connections as 12 are 40 45 connected by suitable nipples with the T-connections 11 and with each other so as to form an outlet conduit extending into the receptacle and transversely across the floor thereof. Rising from each T-connection 12 is a hollow anode 13 whose lower end

50 55 60 65 openings of the T-connections 12 are arranged in line so that the series of hollow electrodes 13 are mounted on said outlet conduit in a row forming in effect a single electrode, subdivided into a plurality of vertical members, which are connected at their upper ends as hereinafter described to a single electric conductor for leading the current thereto. The anode may be formed of carbon or graphite or other desired substances which will be insoluble in the solu-

tions treated. A carbon anode can be readily formed in the hollow tubular shape shown in Fig. 5 and its lower end is provided with a screw threaded portion 14, by which it may be directly screwed into one of the T-connections 12. The walls of the anode are provided with a number of perforations 15 through which the solutions may enter the anode in passing from the cell. Anode members 13 are parallel, and preferably vertical. The upper end of the anode 13 is provided with interior threads and is adapted to be closed by a plug 16 having a screw threaded portion for filling the end of the anode. The upper end of each plug 16 is adapted to be secured to a bus-bar 17, usually by means of a clip 18. The end of the plug is spaced a suitable distance from the bus-bar 17 by the interposition of a block 19 so that when the clip 80 and block are removed, the diaphragm which incloses the anode may be slipped upwardly therefrom past the bus-bar. The branch bus-bars 17 are connected in any desired manner with a longitudinal connecting bus-bar 20 and by this means with the source of electrical energy.

An important feature of the invention also is the diaphragm used for preventing the diffusion of the cupric and ferric compounds above referred to. This diaphragm 24 is preferably made of fibrous material, as for instance, asbestos, cocoanut fiber, cotton, or yucca fiber, the latter of these being preferred as it is quite cheap and plentiful. The said diaphragm is generally made cylindrical and open at the ends, and so as to fit quite snugly the outer contour of the anode member 13. This diaphragm sleeve being more or less flexible or yielding, by 100 reason of its fibrous composition, is able to adapt or conform itself to the anode member and to fit snugly, but removably, thereon. The diaphragm may thus be easily slipped into position upon any of the anode members 13 and can be as readily removed therefrom for cleansing, repair or replacement. It will be observed that the diaphragm is thus also thoroughly supported by the hollow anode without the need of 110 any securing means. It will be readily understood that any number of branches of anodes may be employed in the cell and that any number of anode members 13 may be used upon each branch and in this way 115 the desired area of anode surface within the cell can be secured.

The materials to be treated are introduced into the cell usually through a supply pipe 21 having a series of branch pipes 22 leading therefrom to opposite sides of the cathodes. The incoming solution, carrying copper, for instance, will thus be discharged close to the faces of the cathodes and half of the copper will be deposited thereon. The 120 125 130

other half of the copper is raised to the higher valency under the electrolytic treatment, as indicated by the formula $Cu_2Cl_2 = Cu + CuCl_2$. At the same time the iron present is oxidized forming ferric chlorid. This oxidation takes place at the anode and by providing for a constant flow of the solution toward the anodes, at a rate greater than the rate of diffusion, I am enabled to remove these products of oxidation, and prevent their spreading through the cathode compartment.

In the use of the cell the liquids flow from the pipe 21, which is controlled by valve 15 through the branch pipes 22 into the cell. Thence the liquids pass through the diaphragms 24 and the perforations 15 to the interior of the anode members 13. The liquids then pass into the branch T-connections 20 and the pipe 10 from whence they are delivered from the cell through a valve controlled pipe 25. It will be understood from the above description that the electric action upon the substances treated is secured by connecting the anodes and cathodes with a suitable source of electricity. It will be observed also that the direction of the electric current is opposite to the direction of the fluid flow, and the copper deposited will be carried to the cathodes while the oxidizing of the other substances will take place at the anode and largely in the perforations 15 within the diaphragm so that the ferric and cupric compounds will have no opportunity for diffusion within the cathode compartment. The plugs 16 not only form removable closing means for the upper ends of the anode members but insure the prevention of the escape of any chlorin that may possibly be freed in the solutions.

The anode members 13 which are next to the end walls of cell 5 are generally not perforated upon the sides next to the said walls as indicated in Fig. 4. In all the other anode members the perforations are usually provided entirely around the same as shown in Fig. 5. By not perforating the outer walls of the anode members carried by the end branches of the anode structure, the ferrous and cuprous compounds are prevented from flowing out of the cell until they have been treated by the electric current.

The means for controlling the outflow of the liquids from the cell structure may be somewhat varied without departing from the spirit of the invention. Thus as shown in Fig. 6, each branch of the anode structure may be provided with an individual outflow pipe 26 having a controlling valve 27. Each of the branch pipes 26 is connected with a pipe 28 for conducting the liquids to any desired point for further use. By the individual connections with each branch of the anode structure, the liquids

can be permitted to flow through some of the branches more rapidly than through others in accordance with the electrolytic action within the cell.

Many of the difficulties previously encountered in the construction of cells and particularly of the anode portions thereof, are obviated by the present invention. Carbon graphite or other insoluble anodes can be easily formed as above described and the area of anode surface within the cell can be increased above that usually obtained with previous constructions of cells in common use. The diaphragms which have heretofore been limited in kind and size and been difficult to clean, repair or replace, can be, in accordance with the present invention, made of any desired size and so that they can be easily and quickly removed at any time for cleaning, repairing or replacing. A much larger area of anode surface can be secured by the cylindrical or tubular branch anode structures shown and described, than can possibly be had with a perforated flat or plate anode. The conduits, pipes and fittings of the anode structure and of the outflow system are preferably made of acid and water proof materials, such for instance, as is largely used in laying under-ground electric cables or conductors. Such pipes and fittings are of non-conducting material also and do not carry away any of the current.

What is claimed is:

1. In an electrolytic cell, a receptacle, a conduit extending into the receptacle, and a plurality of tubular electrodes detachably and rigidly mounted on and carried by said conduit, and having perforate walls adapted for passage of electrolyte therethrough.

2. In an electrolytic cell, a receptacle, a conduit extending into the receptacle and having a plurality of openings, and a series of tubular perforate walled electrodes fitting in said openings so as to be rigidly carried by said conduit.

3. In an electrolytic cell, a receptacle, a conduit extending thereto, and having a screw-threaded T-connection, and a tubular perforate walled electrode screwing into said T-connection.

4. In an electrolytic cell, a receptacle, a conduit extending into said receptacle and provided with a series of openings, and a series of tubular perforate walled electrodes fitting in said openings so as to be rigidly carried by said conduit, conducting plugs closing the upper ends of said tubular electrodes, and an electric conductor connected to said plugs of all the electrodes.

5. In an electrolytic cell, a receptacle, an outlet conduit extending into said receptacle, a plurality of hollow perforate walled electrodes detachably and rigidly mounted on and carried by said conduit and com-

- municating therewith, and a diaphragm formed as a sleeve of porous insulating material removably fitting on each of said hollow electrodes.
- 5 6. In an electrolytic cell, a receptacle, an outlet conduit extending into said receptacle, a row of hollow perforate walled anodes mounted on said conduit so as to be carried thereby and communicating with said conduit, a cathode in said receptacle, and means for supplying electrolyte between the said cathode and said anodes.
- 10 7. In an electrolytic cell, a receptacle, a conduit extending thereinto and having a series of T-connections, and a series of hollow perforate walled electrodes fitting in the respective T-connections so as to be carried by said conduit and to communicate therewith.
- 15 8. In an electrolytic cell, a receptacle, a conduit extending thereinto, a series of hollow perforate walled electrodes mounted on said conduit so as to be carried thereby and to communicate therewith, and an electric conductor connected to the upper ends of said electrodes.
- 20 9. In an electrolytic cell, an electrode support formed as a pipe, a plurality of tubular perforated electrodes mounted on said pipe and communicating therewith, and a dia-
- phragm formed as a sleeve of porous material surrounding each of said tubular perforated electrodes.
- 10 10. In an electrolytic cell, a pipe having a portion extending into the cell, a series of parallel tubular pervious electrode members mounted on said pipe portion and communicating therewith, and porous diaphragm sleeves surrounding the respective electrode members.
- 15 11. An anode structure for electrolytic cells comprising an outflow pipe having branches extending into the cell and a series of perforated anode members projecting from each of said branches.
- 20 12. A combined anode and diaphragm comprising a hollow body portion having perforations in its walls and an outlet, an inclosing sleeve of porous material outside said walls, means for connecting the body portion with a source of electrical energy and means for connecting the outlet opening with an outlet pipe for conducting liquids from the interior of said anode.
- 25 In testimony whereof, I have hereunto set my hand, in presence of two witnesses.
- 30 HENRY B. SLATER.
